UNITED STATES PATENT OFFICE.

EDWARD A. REAP AND JAMES C. JOHNSTON, OF ENID, OKLAHOMA.

CORK HOLDER AND LIFTER.

1,074,015.

Specification of Letters Patent. Patented Sept. 23, 1913.

Application filed March 5, 1913. Serial No. 752,188.

To all whom it may concern:

Be it known that we, EDWARD A. REAP and JAMES C. JOHNSTON, citizens of the United States, residing at Enid, in the county of Garfield, State of Oklahoma, have invented a new and useful Cork Holder and Lifter, of which the following is a specification.

This invention relates to a cork holder and lifter.

An object of the present invention is to provide an improved cork lifter and holder which may be readily secured to the neck of any bottle or may be secured thereto prior to the original sale thereof.

A further object is to provide a device to be secured to the neck of a bottle and provided with a lid hingedly secured thereto to the under surface of which lid is secured the bottle stopper.

A further object is to provide a bottle attachment comprising a lid hingedly secured to the neck of a bottle and a corkscrew projecting downwardly therefrom adapted to engage a cork stopper for the holding thereof and to further provide means whereby the cork may be readily inserted within or withdrawn from the neck of the bottle.

A still further object is to carry out these ends in a simple, effective and inexpensive manner.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferable form of my invention is illustrated, in which:

Figure 1 is a view in perspective of my improved device secured upon the neck of a bottle, the bottle being shown in dotted lines. Fig. 2 is a side view in elevation thereof. Fig. 3 is a vertical cross sectional view illustrating a modified form of cork securing means. Fig. 4 is a top plan view.

Referring to the drawings in which similar reference numerals designate corresponding parts throughout the several views, 1 is a bottle provided with the usual

neck 2 into which is adapted to extend the stopper 3 of cork or similar resilient material, the above being taken as the type of apparatus with which my device is intended to be used.

As illustrated in Fig. 1 of the drawings a wire 3' completely encircles the mouth of the bottle and is joined as at 4, the joint being in the nature of the twisting of the wire until the same is drawn tightly against the side walls of the bottle neck. The wire 3' is twisted upon itself as at 5, bent horizontally and then upwardly to form the upstanding arms 6, extending between which and preferably formed integral therewith is the horizontal portion 7 which serves as an axis or shaft about which a lid 8 swings.

The bottle stopper 3 as illustrated in Fig. 2 is provided with the upper surface thereof slightly rounded and the said stopper is spaced a slight distance from the upper lid which allows the cork to aline with the bottle neck previous to the insertion therein. This is of importance as it provides that the cork will always fit within the bottle neck regardless of the length of the cork. The stopper or cork when inserted within the bottle is adapted to lie flush with the upper surface thereof and due to the spacing of the stopper and the lid 8 the upwardly extending arms 6 insure that the lid 8 will be in a horizontal position when the cork or stopper is fully inserted within the bottle. The lid 8 is preferably oval or elliptical in outline, a portion 9 thereof being curled upon itself and inclosing the shaft or portion 7 with which it effects a hinged connection. The lid 8 is provided with the two apertures 10 approximately central thereof and extending therethrough is the means for holding the bottle stopper securely or loosely on the lid.

The form shown in Fig. 1 is a corkscrew and the form illustrated in Fig. 3 comprises a length of wire extending through two apertures formed in the cork the lower ends of which wire are twisted upon themselves and the outlying projections cut off to form a neat appearance. The forward portion of the lid 8 remote from the back 9 is intended to extend beyond the mouth of the bottle as at 11 which provides easy means whereby the lid may be gripped and raised or lowered according to whether the stopper is to be inserted within the bottle or withdrawn therefrom.

From the foregoing it will be apparent that the portion of the wire 3" may be enlarged and strengthened and made of resilient material the ends of which do not meet but are separated a short distance with the result that the device may be attached to any bottle by merely springing the two portions of the wire 3" apart until they pass over the mouth or neck of the bottle and upon 10 the releasing of the same will immediately spring together to firmly grip the neck of the bottle the said construction being fragmentally illustrated in Fig. 2.

It is to be understood that the device as 15 herein disclosed is rather intended to provide means whereby the stopper may be inserted or withdrawn from the bottle and to further provide a holder for the said stopper after having been removed from the bottle. Furthermore, the device is not intended 20 for the locking of a bottle stopper within the neck or is it to be confused with those devices for the initial drawing of the cork, but however, is rather intended to be used as a 25 convenient means whereby the cork may be withdrawn or replaced within the bottle and furthermore will effectually prevent the cork from being lost or misplaced. The cork is withdrawn or inserted within the bottle by 30 a mere raising or lowering of the lid 8 to facilitate which the front portion thereof has been projected as at 11 beyond the mouth of the bottle. The corkscrew attachment extending downward from the lid allows the 35 device to be readily secured upon any bottle and the cork suitably impinged upon the said corkscrew attachment.

The form illustrated in Fig. 2 is rather 40 intended for those instances in which the device is positioned upon a bottle prior to the initial filling thereof, the construction being so strengthened as to render it possi-

ble for the cork to be initially withdrawn from the bottle by a raising of the lid 8.

Having thus described the invention, what 45 is claimed is:—

1. A bottle attachment comprising a member including a horizontal wire, a lid hingedly secured thereto, a bottle stopper with an upper curved surface, and means extending through said lid engaging the said bottle stopper and mounting the same for limited movement.

2. A bottle attachment comprising a member engaging the bottle neck, said member including a horizontally extending wire spaced above the bottle mouth, a lid hingedly secured to said horizontal wire and mounted for rotation in a vertical plane, a bottle stopper with an upper curved surface, and means connected to said lid detachably engaging the said bottle stopper and holding the said stopper for limited movement with respect to the lid.

3. A bottle attachment including a resilient member engaging the mouth of a bottle, and supporting a horizontal wire thereabove, a lid pivotally secured to said horizontal wire and mounted for rotation in a vertical plane thereon, a bottle stopper with an upper spherical surface, means extending through the central portion of said lid and engaging the central portion of said bottle stopper for holding the same to the lid and providing for the limited motion of the same 75 with respect to said lid.

In testimony that we claim the foregoing as our own, we have hereto affixed our signatures in the presence of two witnesses.

EDWARD A. REAP.
JAMES C. JOHNSTON.
